UNITED STATES PATENT OFFICE

Application filed August 4, 1931. Serial No. 555,065.
GILBERT MYERS, OF BOISE, IDAHO

TOY

Application filed August 4, 1931. Serial No. 555,065.

My invention relates to improvements in toys and it consists in the combinations, constructions and arrangements herein described and claimed.

5 An object of the invention is to provide an inexpensive toy whereby a child seated on a cart-like device may cause the latter to revolve around a central standard as an axis.

10 A further object of the invention is to provide a device in which the car may serve as a so-called coaster and in which the propelling device has also the double function of a steering device when the toy is used as a coaster.

15 A further object of the invention is to provide a toy of the type described in which the rotary movement is accomplished within a minimum space, thereby making the toy available for indoor as well as outdoor use.

20 A further object of the invention is to provide a device having relatively few parts but of strong construction so that it is not easily gotten out of order.

25 Other objects and advantages will appear in the following specification and the novel features of the invention will be particularly pointed out in the appended claims.

30 My invention is clearly illustrated in the accompanying drawing forming part of this application, and in which:

Figure 1 is a perspective view of one embodiment of my invention,

Figure 2 is a bottom view of the main board or seat, the legs being broken away and the actuating shaft being shown in section, and

35 Figure 3 is a longitudinal sectional view of a portion of the device.

40 In carrying out my invention I provide an elongated board or seat 1 of the shape shown in the drawing. Near the rear end of this seat are secured legs 2 and 3, respectively. These legs as it will be observed extend at right angles to each other. They are held preferably by means of a metal plate 4 which is secured to the legs, as shown in Fig. 3. A bolt 5 passes through the seat and is held by a nut 6 which bears on the plate 4. Screws 7 secure the plate in position and additional screws 8 may be made use of in order to hold the legs rigidly to the seat.

50 Secured to the front end of the seat and on

the underside thereof, is a block 9 of wood or other suitable material and this block has running therethrough a sleeve 10 which is preferably made of metal. One end of this sleeve has a flange 11 which is secured to the lower portion of the block 9 by means of screws 12. The sleeve 10 extends through the seat 1 and terminates in a headed portion 13. A reinforcing ring 14 of metal is secured to the seat on the upper portion thereof. The sleeve 10 passes through this ring.

55 A shaft 15 passes through the sleeve 10 and is provided with a flange 16 which bears on the flange 11 at the bottom of the sleeve which is secured to the underside of the block 9. The shaft 15 is bent laterally at 16, then upwardly at 17, then laterally at 18 and upwardly at 19. That portion of the shaft 15 between the bends 18 and 19 extends beyond the central axis of the sleeve 10. Handles 17^a and 19^a are provided.

60 At the bottom of the shaft 15 is a device consisting of a frame 20 loosely secured to the shaft in any suitable manner as by a bolt 21. This frame is provided with four wheels 22.

65 The legs 2 and 3 have at their extremities caster wheels 2^a and 3^a, respectively. These wheels may be of any suitable type and may be rubber-tired as shown in the drawing.

70 From the foregoing description of the various parts of the device the operation thereof may be readily understood. The shaft 15 constitutes a crank. The child sits on the seat 1 and grasps the handles 17^a and 19^a. Now when force is used in an effort to turn the shaft 15, the friction created by the pressure of the wheels 22 on the ground or floor will tend to oppose this rotation. The seat of the operator is located so that the weight of the operator is exerted well inside the two outer points of support, thus increasing the friction between the wheels 22 and the ground. Continued pressure on the handles fails to revolve the shaft 15 but results rather that instead of the crank being turned, the seat will itself revolve about the axis of the shaft 15 and thus the child may rotate himself around as long as he continues to exert the turning pressure on the crank. The caster 100

wheels 2^a and 3^a will accommodate themselves to this rotary movement.

Another feature which attends to lend to the easy rotation of the seat and the occupant is that the counteracting weight of the operator's legs when supported alongside of the crank housing further tends to increase the friction at the bottom of the crank and proportionately decreases friction at the outer ends of the supporting legs.

10 The frame 20 has a slight pivotal movement about the bolt so that when the device is being operated on an irregular surface the wheels will at all times remain in full contact with the surface, thus maintaining the friction necessary to prevent turning of the crank. Although the device is mounted on wheels or rollers it is not a vehicle in the usual meaning of the term when it is being used to cause the 15 rotary movement about the axis of the shaft 20 15.

The device is capable of being revolved in either direction. By exerting a turning force on the handles 17^a and 19^a in one direction, the occupant of the car as well as the car 25 itself will be rotated and on reversing the direction of the rotating force the direction of rotation will also be reversed.

One advantage of this device is that it can 30 be instantly used in the manner of coaster and then the crank becomes a steering means and the device may be pushed forwardly in a straight line as with the ordinary coaster and steered with the handle 19^a. The casters 2^a and 3^a will align themselves with the 35 wheels 22.

I claim:

1. A toy comprising an elongated seat, a 40 pair of legs secured to the seat near one end thereof, said legs being at right angles to one another, a caster wheel carried by each leg, a block secured to the underside of the seat near the opposite end thereof, a sleeve extending through the block and seat, said sleeve having a flange engaging the lower surface of the block, a crank shaft having a portion extending through the sleeve and provided with a flange abutting the flange on the sleeve, said crank shaft having a pair 45 of handles, a frame pivotally secured to one end of the crank shaft, and wheels carried by the frame.

2. A toy comprising an elongated seat, a 50 pair of legs secured to the seat near one end thereof, a caster wheel carried by each leg, a block secured to the underside of the seat near the opposite side thereof, a sleeve extending through the block and seat, a crank shaft having a portion extending through 55 the sleeve and provided with a flange for supporting the block, said crank shaft having a pair of handles, a frame pivotally secured to one end of the crank shaft, and wheels carried by the frame.

65 3. A toy comprising an elongated seat, a

pair of legs secured to the seat near one end thereof, a caster wheel carried by each leg, journalling means secured to the seat near the opposite end, a crank shaft extending through the journalling means and having a supporting flange therefor, a frame pivotally secured to one end of the crank shaft, wheels carried by the frame, and a pair of handles disposed on portions of the crank shaft above the seat.

4. A toy comprising an elongated seat, a support rigidly connected to said seat near one end thereof, said support having swivelled anti-friction means at the bottom thereof, a crank shaft extending through the seat near the opposite end thereof, means carried by the seat for journalling the crank shaft, a pair of handles carried by the crank shaft above the seat, a frame secured to one end of the crank shaft below the seat, and wheels carried by the frame.

5. A toy comprising an elongated seat, a support for the seat secured to the latter near one end thereof, swivelled antifriction means carried by the support at the lower end of the latter, a crank shaft extending through the seat near the opposite end, handles for operating the crank shaft disposed above the seat, and wheels carried by the lower end of the crank shaft.

6. A toy comprising a seat, a support secured to the seat near one end thereof and having swivelled anti-friction means at its lower end, a crank shaft passing through the seat near the opposite end, the bent portion of the crank shaft being above the seat, and anti-friction means secured to the crank shaft below the seat.
